UNITED STATES PATENT OFFICE.

CHRISTIAN WM. MEINECKE, OF JERSEY CITY, NEW JERSEY, ASSIGNOR TO MEINECKE & COMPANY, OF NEW YORK, N. Y., A CORPORATION OF NEW JERSEY.

DESIGN FOR A WATER-CUSHION.

45,122.

Specification for Design.

Patented Jan. 6, 1914.

Application filed January 3, 1913. Serial No. 740,038. Term of patent 14 years.

To all whom it may concern:

Be it known that I, CHRISTIAN W. MEINECKE, a citizen of the United States, and resident of Jersey City, county of Hudson, State of New Jersey, have invented a new, original, and ornamental Design for Water-Cushions, of which the following is a specification, reference being had to the accompanying drawing, forming part thereof.

In the drawing the single figure shows my new design of water cushion in plan view.

I claim:

The ornamental design for a water cushion as shown:

In testimony whereof I have hereunto set my hand in the presence of two subscribing witnesses.

CHRISTIAN WM. MEINECKE.

Witnesses:

EDWARD JOHNSON,

DANIEL HOGAN.
